ELECTRIC FUSE SOCKET

Lambert Schmidt, Jr., Brooklyn, N. Y., assignor
to himself, and Louis Freund, New York, N. Y.

Application November 5, 1928, Serial No. 317,227

19 Claims. (Cl. 200—119)

My invention relates to electric fuse sockets, and its principal objects are:

To provide an adapter which enables a small size plug to be inserted in a standard socket, and means for locking the adapter in position, so that thereafter large size plugs cannot be inserted; and to reduce the possibilities of tampering with fuse sockets, and especially unauthorized or improper "shorting" of the circuit within the socket this object being accomplished by providing a movable contact device, or circuit breaker, located either in the socket or adapter; by so forming this movable contact member that bridging of contacts by insertion of a simple metal piece such as a coin, is prevented; and by practically closing the slot which is provided in an accessible part of the socket shell, whereby shorting or bridging of the contacts by a metal piece inserted through this slot, is rendered difficult or impossible.

The circuit breaking device is preferably so constructed or arranged that it is easily placed in a socket of ordinary construction.

The characteristics and advantages of the invention are further sufficiently explained in connection with the following detail description of the accompanying drawings, which show certain exemplifying embodiments. After considering these examples, skilled persons will understand that many variations may be made, and I contemplate the employment of any structures that are properly within the scope of the appended claims.

In the drawings:

Fig. 1 is a vertical (axial) section of a socket structure, embodying the invention in one form.

Fig. 2 is a perspective view of a spring contact operating device.

Fig. 3 is a plan view of a movable contact disc and its contact.

Fig. 4 is a vertical axial section of a socket arranged for a plug adapter, and one suitable locking adapter, constituting a part of my invention, inserted therein.

Fig. 5 is a side elevation of the adapter, with a part in section.

Fig. 6 is a top plan of the same.

Fig. 7 is a section of a standard socket and plug in cooperation with a locking adapter including a movable contact device, and constituting another embodiment of the invention.

Fig. 8 is a side and sectional view of the adapter of Fig. 7.

Fig. 9 is a bottom plan of the same, with a part in section.

In all the examples shown, 1 is the insulating body (such as porcelain) of a standard electric socket, used for the purposes of this invention as a fuse (or "cut-out") socket to receive any known or suitable fuse plug 2. The socket body includes a base 3, and a socket or sleeve portion 4 which is open at one side, as at 5. In this sleeve is the metal shell 6 constituting the outer plug contact. This shell is pressed to screw thread formation 7, has an inturned base flange 8 resting on the bottom of the insulator sleeve, and is cut away at one side, this cut-out or slot 9 being positioned in sleeve opening 5. A conducting strip 10 passes through slot 9 and rests on shell flange 8, the outer end of this strip going to, or constituting one of the circuit terminals 11. The center contact of the socket is the head 12 of a screw 13, which passes through a hole 14 in body 1 and engages in a conducting strip 15 which leads to, or constitutes, the other circuit terminal 16. A disc 17 of insulating material is held down by a screw head 12 upon a circular boss 18 of the base and upon conductor strip 10.

The fuse plug 2, in the form shown, has a body 20 of insulating material threaded as at 21, and 25 the outer contact, for electrical connection with shell 6 is a threaded metal segment 22; the center contact 23, of usual type, in ordinary practice, engages screw head 12 to complete the circuit through the fuse (not shown) located within 30 the plug in the usual way. Any other suitable type of fuse plug may be employed, and the plug and socket, per se, do not form parts of my invention, except as modified in accordance with the invention, or in cooperation with novel features thereof, as now to be fully explained.

It is now customary to furnish fuse plugs having threaded portions of different diameters, sufficiently identified hereafter as "large" and "small" plugs (or threaded portion diameters), 40 these corresponding, for example, to fuse amperage capacities above and below a certain value; and sockets are provided, having "shells" of corresponding diameters; the invention includes adapters which may be inserted in the large size 45 sockets, together with means for locking them in position, so that after insertion of the adapter, only a small size plug can be inserted therein, thus properly limiting the current flow through the particular socket, under control of competent electricians.

Fig. 1 shows any ordinary plug 2 inserted in a properly dimensioned shell 6 without an adapter, while Figs. 4 and 7 each shows an adapter inserted in the socket shell, thereby enabling the use there- 55

in of a plug of smaller thread-diameter than could be used in the same socket, without the adapter. Preferably in both cases, the adapter has a locking device, permitting it to be readily 5 screwed into proper position, but preventing (by engagement with the socket shell), reverse rotation, or unscrewing, and removal by unauthorized persons; so that, for example, an electrician may insert the adapter in a standard or oversize socket and thereafter a standard or oversize plug can- 10 not be inserted, but a small size plug, having a properly predetermined current capacity, must be used.

In all of Figs. 1, 4 and 7, a movable circuit 15 breaker or contact carrier and center contact, carried thereby, is included; in Figs. 1 and 4, this device is arranged in or as a part of the socket; while in Fig. 7 the movable contact device is ar- 20 ranged in and as a part of the adapter.

Referring now to Figs. 1, 2 and 3, in which any 25 standard plug 2 is inserted directly in socket shell 6, without an adapter.

A movable contact carrier 25 is located in the lower (inner) part of the shell and may in some 30 cases, as here shown, be removable; otherwise, it may be secured against removal by studs or lugs 26 punched in the shell wall, or otherwise, as explained in connection with Fig. 7. This contact carrier is of any suitable insulating material, such as synthetic resin composition, hard rubber, bone, etc., and is in the form of a round disc, 35 preferably having a concave upper surface 27, and also a peripheral wall or flange 28 on its lower face, to cooperate with actuating mem- 40 bers (presently referred to) and also forming a chamber for a part of the metal contact. This center contact 29 is located in the center of the carrier, and conveniently is practically in the form of a special stud or rivet, including a stem 45 30 passing through the carrier disc, a lower head 31, located at the under face of the carrier and adapted for contact with the center socket contact 12, and another, small, head or flange 32 formed by "upsetting" the end of the stem, to retain the contact in position.

Cooperating with this contact device is an actuator, in the form of a resilient device tending 50 normally to hold the contact disc in an upward (or outward) position, with head 31 of the contact out of engagement with the socket center contact 12, but permitting the disc to move down (or inward) by engagement with contact 32 of the center contact 23 of the plug, in the act of screwing in the plug, thus establishing the center circuit from socket contact 12 through movable contact 29 to the plug contact 23. Specifically, as here shown, this actuating device consists of a flat ring 35 of suitable resilient metal, located on the insulating disc 17 of the socket, 55 surrounding center contact 12, thereof, and so dimensioned that it cannot establish connection between such contact 12 and the shell 6. This ring has a plurality of integral spring fingers 36, bent up from the normal plane of the ring, and engaging with the under face of disc 25, or specifically, with peripheral wall 28 thereof. Thus, when plug 2 is not in the socket, the spring fingers hold the disc in an upward (or outward) 60 position, with contact 31 out of engagement with socket contact 12; the socket contacts therefore cannot be bridged, to close the circuit, by any ordinarily available means; since for such unauthorized bridging, it is necessary not only to electrically connect the center contact 32 to shell 65 6, but to hold the circuit breaker down against

the force of its spring; and such manipulation is impracticable to persons of ordinary skill or with ordinarily available devices.

When plug 2 is inserted, its center contact en- 70 gages movable contact 29 and moves the disc and said contact down to engage with socket contact 12 and to complete the circuit in the ordinary and proper way.

The concave, or cupped shape of the outer face 75 of the contact disc 25 also prevents bridging the circuit, whether the disc is in open or closed circuit position, by insertion of any simple or easily obtained metal piece, such as a coin, since while such object may be made to engage with the shell wall, it will not engage with the center 15 contact 32, located at the bottom of the depression 27.

In Fig. 4, an adapter 40 is inserted in socket shell 6, for purposes above explained. This adapter may be a simple, short, pressed or "threaded" 20 metal shell dimensioned externally to fit the socket shell, and internally to fit the plug thread; while the latter is of such dimension that in absence of the adapter, it cannot be engaged with the socket shell thread.

Preferably, as above stated, the adapter has a locking device, consisting specifically, as shown, of a wire 41 of stiff, spring metal (see Figs. 5 and 6, and also Fig. 9, which shows substantially the same locking arrangement). This wire is located 30 at the bottom of one of the adapter threads (or grooves) and secured by passing it through two or more perforations 42 in the adapter shell, which may then be pressed to retain the wire in position. One end 43 of the wire is bent out- 35 ward, and its end constitutes in effect a pawl or detent, which, when the adapter is screwed into the socket shell, slides freely in contact with the shell surface; but upon any force being applied to rotate the adapter reversely, this detent 40 or prong bites into the socket shell, and prevents such rotation, and removal of the adap'er. Therefore, when once inserted, only plugs of pre- 45 determined dimension, and "amperage" can be inserted in the socket.

In Fig. 4, the adapter 40 may serve to prevent 45 removal of the circuit breaking device, disc 25 being of such diameter that it cannot be brought up through the adapter.

In Figs. 7, 8 and 9, the movable contact de- 50 vice is located in the adapter, instead of in the socket. The adapter and its detent device may be as above described, except that the adapter body, or shell 50, is longer, having a lower (or inner) cylindrical portion 51 of somewhat re- 55duced diameter, terminating in an inturned flange 52. The movable contact disc 25 is located in the cylindrical lower portion 51 of the adapter, and the actuating ring 53 rests on flange 52, with its spring fingers 36 tending to support the 60 contact disc and maintain contact 31 out of engagement with center socket contact 12.

Means is in this case provided to prevent dis- 65 placement, or removal of the contact disc, consisting of an annular bead 55 pressed inwardly in the adapter shell. Similar means may be provided, if desired, in Figs. 1 and 4, to retain the movable contact device in position in the socket shell.

The adapter of Fig. 7 also has a locking, or 70 detent device 41 substantially similar to that described in connection with Fig. 4 (see also Figs. 8 and 9), the detent wire being in this case located above the movable contact chamber, and 75

at the lower end of the threaded portion of the shell.

In both of Figs. 1 and 4, the side wall of the contact carrier 25 is so dimensioned or arranged that it is impossible or impracticable to "short" the socket contacts by a metal piece inserted through the shell slot 8; whereas in absence of this protective feature, such tampering is relatively easy.

In Fig. 7, the same function is accomplished by the lower part of the adapter, which partly or entirely blocks off the shell slot 8, at its inner side.

I claim:

1. An adapter for an electric or fuse socket, comprising a threaded metal shell insertible in the socket shell, and adapting it to receive a small size plug, and a detent device in the adapter cooperating with the socket shell, to permit insertion of the adapter and prevent outscrewing thereof, said detent consisting of a spring wire inserted through the adapted wall and having a resilient point to engage the socket shell.

2. For use in an electric fuse socket having a shell and a center contact, a contact carrier arranged for axial movement within the shell and having a central contact piece to connect the center contact of a plug with the center contact of the socket, means for causing movement of said contact carrier in one direction, and means for limiting the movement of said contact carrier away from said center contact.

3. For use in an electric fuse socket having a shell and a center contact, a movable contact carrier having a central contact piece to connect the center contact of a plug with the center contact of the socket, and an actuator adapted to be located within the socket shell below the contact carrier and having means urging the latter outward to break the socket circuit in absence of a plug therein.

4. For use in an electric fuse socket having a shell and a center contact, a movable contact carrier having a central contact piece to connect the center contact of a plug with the center contact of the socket, and an actuator adapted to be located within the socket shell below the contact carrier and having means urging the latter outward to break the socket circuit in absence of a plug therein, the circuit being closed by downward movement of the contact carrier, actuated by insertion of a plug.

5. For use in an electric fuse socket having a shell and a center contact, a contact carrier arranged for axial movement within the shell and having a central contact piece to connect the center contact of a plug with the center contact of the socket, the contact carrier being located to substantially close a slot in the shell wall and obstruct the insertion of an object therethrough to bridge the socket terminals.

6. For use in an electric fuse socket having a shell and a center contact, a movable contact carrier having a central contact piece to connect the center contact of a plug with the center contact of the socket, and an actuator adapted to be located within the socket shell below the contact carrier and having means urging the latter outward to break the socket circuit in absence of a plug therein, said actuator comprising an annular disc having spring fingers for operating the contact carrier.

7. For use in an electric fuse socket having a shell and a center contact, a movable contact carrier having a central contact piece to connect

the center contact of a plug with the center contact of the socket, and an actuator adapted to be located within the socket shell below the contact carrier and having means urging the latter outward to break the socket circuit in absence of a plug therein, said actuator comprising an annular disc having spring fingers for operating the contact carrier, and means retaining the contact carrier in the socket shell.

8. In combination with a socket of character set forth, an adapter including a lower portion substantially blocking an opening in the socket shell and interfering with insertion of an object therethrough to bridge the socket contacts, and a circuit breaker in the adapter. 15

9. In combination with a socket of character set forth, an adapter including a lower portion substantially blocking an opening in the socket shell and interfering with insertion of an object therethrough to bridge the socket contacts, 20 and a circuit breaker in the adapter, said circuit breaker including a movable contact piece, and a resilient actuator thereunder.

10. In combination with a socket of character set forth, an adapter including a lower portion 25 substantially blocking an opening in the socket shell and interfering with insertion of an object therethrough to bridge the socket contacts, and a circuit breaker in the adapter, said circuit breaker including a movable contact piece, 30 and a resilient actuator thereunder, and means preventing removal of said contact piece.

11. In combination with a socket as described, a disc of insulating material insertible therein and adapted for axial movement within the socket and 35 having a concave outer surface and a contact piece passing centrally through the disc and having its outward end near the bottom of said cuffed surface, whereby to prevent "bridging" 40 from a surrounding shell surface to said center contact, and means for limiting the movement of said disk away from the bottom of said socket.

12. In combination with an electric socket of the character described including a metal screw shell and a center contact, a disk of insulating 45 material retained for moderate axial movement within the shell near the bottom thereof and having at its center a metal contact piece extending through the disk and arranged for engagement with the center contact of the socket and with 50 the center contact of an ordinary plug inserted in the socket shell, spring means normally urging the disk to outward position with its contact piece spaced from the center contact of the socket, and means for limiting the outward movement of said 55 disk.

13. In combination with an electric socket of the character described including a metal screw shell and a center contact, a disk of insulating material retained for moderate axial movement 60 within the shell near the bottom thereof and having at its center a metal contact piece extending through the disk and arranged for engagement with the center contact of the socket and with the center contact of an ordinary plug inserted 65 in the socket shell, a spring acting between the shell bottom and the disk and normally urging the disk to outward position and a stop means for determining the outward position of said disk under the action of said spring. 70

14. For use in an electric socket of character described including a metal screw shell and a center contact, an adapter insertable in the shell and including a substantially cylindrical threaded shell, and within the adapter shell near the bot- 75

- 5 tom thereof a disk of insulating material retained for slight axial movement, the disk having at its center a contact piece extending through it and arranged for engagement with the socket center contact and the center contact of an ordinary plug inserted in the adapter shell.
15. For use in an electric socket of character described including a metal screw shell and a center contact, an adapter insertable in the shell and including a substantially cylindrical threaded shell, and within the adapter shell near the bottom thereof a disk of insulating material retained for slight axial movement, the disk having at its center a contact piece extending through it and arranged for engagement with the socket center contact and the center contact of an ordinary plug inserted in the adapter shell, the bottom of the adapter shell being open to permit engagement of the disk contact with the socket center contact.
16. For use in an electric socket of character described including a metal screw shell and a center contact, an adapter insertable in the shell and including a substantially cylindrical threaded shell, and within the adapter shell near the bottom thereof a disk of insulating material retained for slight axial movement, the disk having at its center a contact piece extending through it and arranged for engagement with the socket center contact and the center contact of an ordinary plug inserted in the adapter shell, and spring means intermediate the bottom portion of the adapter shell and the disk and normally urging the disk to outward position.
- 30 17. For use in an electric socket of character described including a metal screw shell and a center contact, an adapter insertable in the shell and including a substantially cylindrical threaded shell, and within the adapter shell near the bottom thereof a disk of insulating material retained for slight axial movement, the disk having at its
- center a contact piece extending through it and arranged for engagement with the socket center contact and the center contact of an ordinary plug inserted in the adapter shell, the adapter shell having at its bottom an inturned flange, and spring means intermediate the flange and the disk and normally urging the latter to outward position.
18. In combination with an electric socket of the character described including a metal screw shell and a center contact, a disk of insulating material retained for moderate axial movement within the shell near the bottom thereof and having at its center a metal contact piece extending through the disk and arranged for engagement with the center contact of the socket and with the center socket of an ordinary plug inserted in the socket shell, and spring means normally urging the disk to outward position with its contact piece spaced from the center contact of the socket, the disk having its outer face concaved to prevent shorting by insertion of a simple metal object and to permit engagement of the center contact of an ordinary plug with the disk contact piece.
- 25 19. For use in an electric socket of character described including a metal screw shell and a center contact, an adapter insertable in the shell and including a substantially cylindrical threaded shell, and within the adapter shell near the bottom thereof a disk of insulating material retained for slight axial movement, the disk having at its center a contact piece extending through it and arranged for engagement with the socket center contact and the center contact of an ordinary plug inserted in the adapter shell, the disk having its outer face concaved to prevent shorting by insertion of a simple metal object and to permit engagement of the center contact of the plug with the disk contact piece.

40 LAMBERT SCHMIDT, JR.
